CLAIM

The ornamental design for a sensory toy, as shown and described.

DESCRIPTION

FIG. 1 is a perspective view of a sensory toy of the present design, with a first component of the sensory toy positioned atop a second component of the sensory toy;

FIG. 2 is a bottom perspective view of the sensory toy of the present design, with the first component of the sensory toy positioned atop the second component of the sensory toy;

FIG. 3 is an exploded view of the sensory toy of the present design, with the first component of the sensory toy positioned above the second component of the sensory toy;

FIG. 4 is a rear right side perspective view of the second component of the sensory toy of the present design;

FIG. 5 is a bottom perspective view of the second component of the sensory toy of the present design;

FIG. 6 is a front view of the second component of the sensory toy of the present design;

FIG. 7 is a right side view of the second component of the sensory toy of the present design;

FIG. 8 is a rear view of the second component of the sensory toy of the present design;

FIG. 9 is a left side view of the second component of the sensory toy of the present design;

FIG. 10 is a top view of the second component of the sensory toy of the present design;

FIG. 11 is a bottom view of the second component of the sensory toy of the present design;

FIG. 12 is a rear right side perspective view of the first component of the sensory toy of the present design;

FIG. 13 is a bottom perspective view of the first component of the sensory toy of the present design;

FIG. 14 is a rear view of the first component of the sensory toy of the present design;

FIG. 15 is a front view of the first component of the sensory toy of the present design;

(Continued)

FIG. 16 is a right side view of the first component of the sensory toy of the present design;

FIG. 17 is a left side view of the first component of the sensory toy of the present design;

FIG. 18 is a top view of the first component of the sensory toy of the present design; and,

FIG. 19 is a bottom view of the first component of the sensory toy of the present design.

In the drawings, the broken lines depict environmental subject matter only and form no part of the claimed design.
